UNITED STATES PATENT OFFICE.

GEORGE A. DOHN AND FREDRICK G. MYERS, OF SANTA ROSA, CALIFORNIA.

CARPET-SWEEPER ATTACHMENT.

1,175,723.

Specification of Letters Patent. Patented Mar. 14, 1916.

Application filed December 22, 1914. Serial No. 878,568.

To all whom it may concern:

Be it known that we, GEORGE A. DOHN and FREDRICK G. MYERS, citizens of the United States, residing at Santa Rosa, in the county of Sonoma and State of California, have invented new and useful Improvements in Carpet-Sweeper Attachments, of which the following is a specification.

10 The invention relates to a carpet sweeper attachment, and more particularly to the class of sprinklers for carpet sweepers.

15 The primary object of the invention is the provision of an attachment of this character wherein the brush within the carpet sweeper can be sprinkled for collecting dirt and dust during the working of the sweeper.

20 Another object of the invention is the provision of an attachment of this character wherein the amount of fluid to be delivered to the brush of the sweeper can be regulated, the attachment being of novel form for assuring the proper sprinkling of the brush in the sweeper and also the perfect working of the same.

25 A further object of the invention is the provision of an attachment of this character which can be readily applied to a carpet sweeper without altering or rearranging 30 any of its parts, and also which is simple in construction, thoroughly reliable and efficient in its action, and inexpensive in manufacture.

35 With these and other objects in view, the invention consists in the construction, combination and arrangement of parts as will be hereinafter fully described, illustrated in the accompanying drawing, and pointed out 40 in the claim hereunto appended.

45 In the drawing:—Figure 1 is a vertical longitudinal sectional view through a carpet sweeper with the attachment constructed in accordance with the invention applied thereto. Fig. 2 is a vertical transverse sectional view thereof.

Similar reference characters indicate corresponding parts throughout the several views in the drawing.

50 Referring to the drawing in detail, A designates a portion of the body or casing of a carpet sweeper, which is of the ordinary well-known construction, having the usual driving wheels or rollers B which

55 operate the revolving brush C designed to clean carpets, floors or the like, while sup-

ported upon the body or casing is the attachment hereinafter fully described.

The attachment comprises a tank 5 adapted to contain water or cleaning fluid, 60 and is superimposed upon the top of the body or casing A, the straps 6 being designed to fix the tank 5 thereon. Located centrally within the tank 5 is an outlet tube 7 which extends through the bottom of the 65 said tank and the top of the body or casing A for engagement with the coupling nipple 8 of a sprinkling head in the form of a pipe 9 having a plurality of outwardly tapered spaced spray nozzles 10 which project into 70 the path of the bristles of the brush C for delivering fluid thereto.

Threaded in the outlet tube 7 within the tank 5 is a needle valve 11 which is adapted to engage in a valve seat 12 formed in the 75 nipple 8, the tube 7 being formed with diametrically opposed apertures or holes 13 for delivering fluid from the tank 5 into the head 9 on the opening of the needle valve 11 which, at its outer end, is formed with a 80 hand disk 14 so that it may be manually manipulated for the adjustment thereof to regulate the supply of fluid from the tank 5 to the spraying head 9, which delivers the fluid to the brush C of the sweeper. 85

The head 9 is fastened interiorly of the body or casing A through the medium of strap hangers 15 which are fastened to the inner face of the top of the body or casing A in any suitable manner. The tank 5 is 90 formed with a rounded bottom 16 so that the fluid therein will be directed to the apertures or holes 13 which are located contiguous to the lowermost point of the bottom 16 so that the contents of the tank 5 can 95 be readily drained therefrom.

The top of the tank 5 is fitted with a capped filling neck 17 through which is introduced the fluid into the tank 5 on the removal of the cap from the said neck. 100

By adjusting the needle valve 11 the required amount of fluid from the tank 5 will be delivered to the brush C of the sweeper during the use thereof.

From the foregoing description, taken in 105 connection with the accompanying drawing, the construction and manner of operation of the device will be clearly understood, and therefore a more extended explanation has been omitted.

110 What is claimed is:—
The combination with a carpet sweeper,

of an attachment comprising a water reservoir fixed upon the body of the sweeper and having a central vertically disposed perforated tube interiorly thereof and extended through the top of the body of said sweeper, a delivery pipe interiorly of the body of the sweeper and having a plurality of discharge nozzles at intervals thereof throughout the length of the same, an externally threaded nipple on the pipe and detachably engaged in the inner end of the tube to form a valve seat, and a needle

valve adjustably threaded in the tube and engageable in the valve seat formed by the nipple to regulate the fluid supply from the 15 reservoir to the pipe.

In testimony whereof we affix our signatures in presence of two witnesses.

GEORGE A. DOHN.
FREDRICK G. MYERS.
